UNITED STATES PATENT OFFICE.

WILLIAM M. DUNCAN, OF ALTON, ILLINOIS.

FURNACE.

Application filed August 28, 1922. Serial No. 584,748.

To all whom it may concern:

Be it known that I, WILLIAM M. DUNCAN, a citizen of the United States of America, a resident of Alton, in the county of Madison, State of Illinois, have invented certain new and useful Improvements in Furnaces, of which the following is a full, clear, and exact description, reference being had to the accompanying drawings, forming a part of this specification.

This invention relates to improvements in furnaces, and more particularly to a furnace equipped with a traveling chain grate from which heat is transmitted to a boiler or the like. The main object of the invention is to produce a simple, efficient and inexpensive structure of this kind including a traveling grate located beyond the vertical projection of the boiler, where it will not weaken the boiler support nor require expensive excavations below the boiler.

The traveling chain grate is preferably located in a combustion chamber adjacent to but entirely beyond the projection of the boiler, and the grate travels in a course approximately at a right angle to the boiler. A flame outlet at one side of the combustion chamber provides for the delivery of heat to the boiler, and the flame moves transversely of the grate to pass through the flame outlet. Consequently, a very narrow grate can be used to obtain a wide flame below the boiler, and this results in a saving in the initial cost of the mechanical stoker, the width of the flame being determined by the length of the grate, instead of by the width of the grate.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a fragmentary view of one end of a boiler, or still, equipped with a heating plant embodying the features of this invention, the combustion chamber being shown in section.

Fig. II is a fragmentary vertical section taken approximately through the middle of Fig. I.

A designates a combustion chamber having side walls 1 and 2, a front wall 3, a rear wall 4 and a top wall 5, the latter being formed by blocks 5' suspended from hanger bars 6. 7 designates supporting rods, each passing through a row of the blocks 5' and also through some of the hanger bars 6. The hanger bars 6 are supported by channels 8, to which they are secured by means of pins 9, as shown in the drawings.

The side wall 1 of the combustion chamber forms the front wall of the heating chamber B, and a flame outlet 10 is formed in the upper portion of wall 1 to provide for the transmission of heat from the combustion chamber A to the heating chamber B. 11 designates a boiler, or still, forming the top wall of the heating chamber B and adapted to be heated by the flame passing through the flame outlet 10. An arch 12 is located adjacent to the top of the flame outlet and directly below one end of the boiler. The boiler and heating chamber lie at approximately a right angle to the combustion chamber A, and said chamber A is preferably located entirely beyond the vertical projection of the boiler.

G designates an endless traveling chain grate arranged in the combustion chamber A, entirely beyond the projection of the boiler and adapted to travel in a course approximately at a right angle to the boiler. The grate herein shown is narrower than the boiler, that is, the transverse dimension of the grate is less than the transverse dimension of the boiler, and one of its traveling sides is adjacent to the side wall 1 of the combustion chamber but below the flame outlet 10 in said wall to provide for the upward delivery of a relatively wide flame from the narrow grate and through said flame outlet. The flame passes upwardly from the top of the grate and thence transversely of the grate, so as to escape through the flame outlet 10 and into the heating chamber B. To pass from the combustion chamber A to the heating chamber B, the flame moves away from the right side of the traveling grate (Fig. II) and across the left side thereof. As an illustration of a suitable traveling grate structure, I have shown endless rows of grate links 13 pivotally connected together at 14 and provided

with a rotary drive shaft 15 to which a suitable number of drive wheels 16 is secured. The fuel-supporting upper portion of the

endless grate travels on tracks 17, and the lower portion thereof travels on tracks 18. To support the rear end portion of the grate, each track 17 may be provided with a curved end portion 17', as shown in Fig. I. Draft boxes 19 are arranged transversely of the grate to provide for the delivery of a forced draft through the fuel-supporting upper portion of the grate, each draft box being open at the top for the discharge of the draft and provided at one end with a draft inlet 20 (Fig. II) formed in one side of a passageway 21 into which air may be forced by means of any suitable blower. By arranging my grate in the manner illustrated I make it possible to employ a grate which is considerably narrower than the associated boiler. Heretofore it has been necessary that the grate be approximately as wide as the boiler, so that the flame would be evenly distributed over a considerable portion of the boiler. However, because of the arrangement of the grate of the furnace disclosed herein with relation to the boiler an even distribution of flame over a considerable portion of the boiler is obtained with a comparatively narrow grate.

The chain grate is mounted between side walls 22, and to prevent leakage of fuel from the grate, closure bars 23 may be arranged on the upper edges of these walls 22 so as to engage the traveling side edges of the grate. 24 designates tubes located above but adjacent to the bars 23 so as to confine the fuel.

The endless chain grate is preferably inclined upwardly from the front to the rear of the combustion chamber A, and the bottom of the flame outlet 10 is approximately parallel with the inclined grate, as shown by Fig. I. A fuel hopper 25 is located above the lower end of the inclined grate and an ash compartment 26 is formed below the upper end of said inclined grate, the ash compartment being entirely beyond the vertical projection of the boiler to permit free removal of the ashes therefrom. Fuel introduced into the hopper 25 escapes through the opening 25' at the bottom thereof and onto the top of the traveling grate, the ashes being discharged from the upper end of the grate and permitted to drop by gravity into the ash compartment 26 at the righthand side of Fig. I.

It is important to observe that the specific structure herein disclosed includes a combination having two main features, and to obtain the beneficial results herein pointed out each of these features is important. First, the traveling grate is located entirely beyond the projection of the boiler where it can be erected without weakening the boiler support and without requiring expensive excavations below the boiler. This materially reduces the cost of the structure

and provides for the discharge of ashes at a point entirely beyond the boiler, thus avoiding the use of expensive means for removing the ashes. Second, to produce an entirely practicable structure having these advantages, the grate travels in a course approximately at a right angle to the boiler, and a wide flame passes transversely of the grate and away from one side thereof to enter the space below the boiler. 75

I claim:

1. A furnace provided with a combustion chamber, a heating chamber at one side of said combustion chamber, said combustion chamber having a flame outlet at said side 80 to provide for the delivery of flame to said heating chamber, a boiler arranged directly above said heating chamber but beyond the vertical projection of said combustion chamber, and a single endless chain grate arranged in said combustion chamber and traveling in a course approximately at a right angle to said boiler, said endless chain grate being narrower than said boiler. 85

2. A furnace provided with a heating 90 chamber, a boiler arranged directly above said heating chamber and forming part of the top wall thereof, a combustion chamber located entirely beyond the vertical projection of said boiler and heating chamber, a single endless chain grate arranged in said combustion chamber and traveling in a course approximately at a right angle to said boiler, one side of said endless chain grate being adjacent to but beyond the vertical projection of said boiler and heating chamber, and one side of said combustion chamber being in free and direct communication with said heating chamber to provide for the delivery of flame across said side of 105 the grate, said endless chain grate being narrower than said boiler. 100

3. A furnace provided with a boiler, a combustion chamber located adjacent to one end of the boiler but entirely beyond the vertical projection of the boiler, one side of said combustion chamber having a flame outlet leading to the boiler, and a single endless traveling chain grate narrower than said boiler, said grate being in said combustion 110 chamber beyond the boiler and traveling in a course approximately at a right angle to the boiler, and one of the sides of said grate being adjacent to but lower than said flame outlet to provide for the upward delivery 120 of a relatively wide flame from the narrow grate and through said flame outlet.

4. A furnace provided with a combustion chamber, a heating chamber at one side of said combustion chamber, said combustion chamber having a flame outlet at said side to provide for the delivery of flame to said heating chamber, a boiler arranged directly above said heating chamber but beyond the vertical projection of said combustion chamber- 125 130

ber, an endless chain grate arranged in said combustion chamber and traveling in a course approximately at a right angle to said boiler, one of the sides of said grate being adjacent to said side of the combustion chamber and below said flame outlet to provide for the delivery of flame across said side of the grate, said endless grate being inclined upwardly from the front to the rear of said combustion chamber, and the bottom of said flame outlet being approximately parallel with the inclined grate, a fuel hopper located above the lower end of the inclined grate, and an ash compartment below the upper end of said inclined grate, said ash compartment being entirely beyond the vertical projection of said boiler.

5. A furnace provided with a combustion chamber, a heating chamber at one side of said combustion chamber, said combustion

chamber having a flame outlet at said side to provide for the delivery of flame to said heating chamber, a boiler arranged directly above said heating chamber but beyond the vertical projection of said combustion chamber, an endless chain grate arranged in said combustion chamber and traveling in a course approximately at a right angle to the axis of the boiler, one of the sides of said grate being adjacent to said side of the combustion chamber and below said flame outlet to provide for the delivery of flame across said side of the grate, a fuel hopper located above one end of said grate, and an ash compartment below the other end of said grate, said ash compartment being entirely beyond the vertical projection of said boiler.
